UNITED STATES PATENT OFFICE

2,379,257

AERIAL BOMB

James Lloyd Scott, Gaston, N. C.

Application April 29, 1943, Serial No. 485,047

1 Claim.

(Cl. 102—5)

The present invention relates to new and useful improvements in aerial bombs, and has for its primary object to provide, in a manner as hereinafter set forth, a device of this character which, when it explodes, will be highly destructive to both life and property over a comparatively large area.

Other objects of the invention are to provide an aerial bomb of the character described which will be comparatively simple in construction, strong, durable, reliable in use, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of an aerial bomb constructed in accordance with the present invention.

Figure 2 is a view in vertical section through the device, taken substantially on the line 2—2 of Figure 1.

Figure 3 is a horizontal sectional view, taken substantially on the line 3—3 of Figure 1.

Figure 4 is a detail view in vertical section, taken substantially on the line 4—4 of Figure 2.

Figure 5 is a detail view in elevation of the upper portion of the impact actuated plunger rod or stem.

Figure 6 is a view of a slight modification to be dropped in water, portions being broken away in section.

Figure 7 is an elevational view of the lower portion of the modified plunger rod.

Figure 8 is a bottom plan view of the modified plunger.

Referring now to the drawings in detail, it will be seen that reference numeral 1 designates a cylindrical shell of suitable metal, said shell including a substantially conical lower portion 2 having a vertical opening or passage 3 in its lower end portion.

Extending into the shell 1 from the periphery thereof is a multiplicity of radial barrels 4 having beveled inner ends 5. The barrels 4 are for the reception of explosive projectiles 6 having mounted therebehind in said barrels explosive charges 7. As best seen in Figure 2 of the drawings, the containers for the explosive charges 7 are beveled on their inner ends to conform substantially to the corresponding ends of the barrels 4. Firing caps 8 are provided for the explo-

sive charges 7. Arms 9 extend inwardly and downwardly from the lower portions of the barrels 4. Angular hammers 10 are pivotally mounted on the arms 9 for engagement with the firing caps 8.

Mounted in the upper end 11 of the shell 1 is a firing cap 12. An impact actuated plunger rod 13 extends slidably through the opening 3 into the shell 1. It will be observed that the upper end of the plunger rod 13 is adjacent to but spaced from the cap 12. The plunger rod 13 is slidable in vertically spaced bearings or guides 14 which are provided therefor in the shell 1. The substantially conical lower portion 2 of the shell 1 is weighted, as at 15. Above the weighted portion 15, the shell 1 contains an explosive 16.

Lugs 17 project from the plunger rod 13 adjacent the inner ends of the barrels 4. The lugs 17 are beveled and engaged beneath the angular hammers 10.

It is thought that the manner in which the bomb functions will be readily apparent from a consideration of the foregoing. Briefly, when the bomb is dropped, the weighted conical end portion 2 thereof causes the projecting end of the plunger rod 13 to strike first. Upon impact, the plunger rod 13 is moved upwardly in the shell 1 and the lugs 17 cause the angular hammers 10 to strike the firing caps 8 for igniting the charges 7 simultaneously in the barrels 4 for shooting the explosive projectiles 6. Immediately after this occurs, the plunger rod 13 strikes the firing cap 12 for igniting the explosive 16 in the shell 1. The lower portion of the plunger rod 13 is provided with a shear ring or collar 18 for preventing the bomb being exploded accidentally.

The bomb shown in Figures 1 to 5, inclusive, of the drawings is primarily for use on land. The embodiment illustrated in Figures 6, 7 and 8 of the drawings is intended to be dropped into water. Accordingly, the plunger rod 13 is provided, on its lower end, with a substantially concavo-convex striking head 19 to insure proper actuation of said plunger rod upon impact with the water.

It is believed that the many advantages of an aerial bomb constructed in accordance with the present invention will be readily understood, and although preferred embodiments are as illustrated and described, it is to be understood that further modifications and changes in the details of construction may be resorted to which will fall within the scope of the invention as claimed. For example, an explosive may be substituted for the weight 15 in the nose of the bomb and the upper or rear end thereof may be provided with

stabilizing fins for directing said nose downwardly when the bomb is dropped.

What is claimed is:

An aerial bomb comprising a shell, an explosive in the shell, a multiplicity of barrels extending radially into the shell from the periphery thereof and having downwardly and outwardly beveled inner ends, projectiles in the barrels, explosive charges in the barrels behind said projectiles, containers for said explosive charges beveled on the inner ends to conform substantially to the beveled inner ends of the barrels, firing caps for the explosive charges, inwardly and downwardly inclined arms projecting from the barrels, angu-

lar hammers pivotally mounted on the arms and swingable upwardly and outwardly to strike the caps for firing the explosive charges, a longitudinally movable impact operated plunger rod slidably mounted in and axially of the shell and projecting from the lower end of the latter, beveled lugs on the plunger rod engageable with the hammers for actuating said hammers, and a firing cap for the first-named explosive in the other end portion of the shell, the plunger rod being engageable with the second-named cap for firing same after actuating the hammers.

JAMES LLOYD SCOTT.
